Primary Examiner — Catherine Tuttle(74) *Attorney, Agent, or Firm* — Staas & Halsey LLP(57) **CLAIM**

The ornamental design for a toy top, as shown and described.

DESCRIPTION

FIG. 1 is a front view of the toy top showing my design;
 FIG. 2 is a rear view thereof;
 FIG. 3 is a right side view thereof;
 FIG. 4 is a left side view thereof;
 FIG. 5 is a top view thereof;
 FIG. 6 is a bottom view thereof;
 FIG. 7 is a top perspective view thereof;
 FIG. 8 is a bottom perspective view thereof; and,
 FIG. 9 is a perspective view showing the components of the design in a disassembled state.
